(57) **CLAIM**

The ornamental design for a reach truck, as shown and described.

DESCRIPTION

FIG. 1 is a perspective view of the reach truck taken from the right rear showing our new design;

FIG. 2 is a perspective view of the reach truck taken from the left rear thereof;

FIG. 3 is a perspective view of the reach truck taken from the left front thereof;

FIG. 4 is a perspective view of the reach truck taken from the right front thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken line showing in the figures is included for the purpose of illustrating environment and forms no part of the claimed design.
